UNITED STATES PATENT OFFICE.

RICHARD R. SMITH, OF TORRANCE, CALIFORNIA, ASSIGNOR TO UNION TOOL COMPANY, OF TORRANCE, CALIFORNIA, A CORPORATION OF CALIFORNIA.

UNDERREAMER.

Application filed February 20, 1922. Serial No. 538,001.

To all whom it may concern:

Be it known that I, RICHARD R. SMITH, a citizen of the United States, residing at Torrance, in the county of Los Angeles and State of California, have invented a new and useful Improvement in Underreamers, of which the following is a specification.

This invention relates to an improvement in underreamers of the general type in which the cutters are suspended upon a spring rod functioning to expand the cutters to cutting or reaming position.

An object of the invention is to provide a removable cutter supporting key associated with the spring rod and a cooperating means for locking the key against displacement.

Another object is to provide with a removable cutter supporting key associated with a spring rod and engaging in transverse openings in the cutters and removable through one of said openings after first being moved to a tilted position, means associated with one of the cutters preventing such tilting movement of the key until said means is first displaced.

A further object is to provide a structure in which the cutters, key and spring rod have a positive coincident vertical movement in both directions.

Various other objects and advantages will be more fully apparent from the following description and the accompanying drawings, which form a part of this disclosure, and which illustrate a preferred form of embodiment of the invention.

Of the drawings:

Fig. 1 is a side elevation of the lower end of an underreamer embodying my improvements.

Fig. 2 is a vertical section on line 2—2, of Fig. 1.

Fig. 3 is a perspective view of the key locking means.

Fig. 4 is a perspective view of the cutter supporting key.

Described in general terms, the underreamer illustrated in the drawings consists of a body 1 having a central bore in which slides a spring rod or mandrel 2 normally subjected to an upward tension of a spring 3 which is positioned in a spring chamber 4 and surrounds the rod. The lower portion of the body has opposed open slipways 5 on opposite sides of the rod 2 in which

slide the shanks 6 of the respective cutters or slips 7, the side walls of the cutter shanks being provided with out-thrust bearing ribs 8 adapted to engage in corresponding grooves 9 in the side walls of the slipways 5. 60 The inner face of each shank 6 is cut away to form an inclined shoulder 10 which engages under the respective expanding shoulder 11 at the lower end of the body when the cutters are in collapsed position. 65 As thus far described the construction shown follows a general form of structure more or less common to several well known makes of underreamers and it is thought that specific or further description of structure or operation would be superfluous. 70

The cutters or slips 7 are supported upon the lower end of the rod 2 by a removable key 12 which loosely engages through a transverse slot 13 in said rod with its opposite ends or tangs extending into slots 14 in the shanks 6 of the respective slips. One of the slots, for example the right hand slot, is of just sufficient vertical depth to receive the adjacent end of the key and maintain 80 substantial engagement with its edges. The medial portion of the key 12 has an extension or wing 15 which projects upwardly between the two cutter shanks so that as long as the key is maintained in a normal 85 position it is retained against displacement. At the outer ends the upper edge of the key is included downwardly, as at 16, so as to permit a tilting of the cutters or slips during their vertical movements in the slipways incident to a collapsing or expanding of the cutters. 90

In removing the slips or cutters 7 from the body it is first necessary to remove the key 12 through the slot 14 of one of the cutters and for this reason said slot, as for instance that of the left hand cutter in Fig. 2, is of considerably greater vertical width than the end of the key, so that it is extended lower than that of the opposite cutter to permit a tilting of the key and its removal endwise through the slot of said cutter shank, as indicated in dotted lines. This tilting is facilitated because I allow clearance above and below the right hand tang of the key in the slot of the right hand cutter as illustrated in Fig. 2. It will be understood that such tilting of the key 12 for subsequent removal, is necessary in order that the extension 15 may clear the up- 110

per edge of the slot 14, and it will also be evident that to accomplish a removal of the key 12 it will be necessary to pull downwardly upon the spring rod 2. Such downward pull on the spring rod is effected by engaging a rod 17, as indicated in dotted lines in Fig. 2, into a screw threaded recess in the lower end of the spring rod, and applying sufficient pulling power to said rod 17 to overcome the tension of the spring 3. The inclined edge 16 on the end of the key remote from the locking member facilitates this tilting of the keys, see Fig. 1.

It has been found desirable in this type of underreamer to provide some means of positively locking the key against removal so as to obviate any likelihood of the parts becoming deranged through use or wear and to prevent an accidental loss of the key, especially while the underreamer is being operated in a well bore, as such accidental loss of the key would result in a loss of both cutters.

To positively lock the key 12 in assembled position I provide a lock member 20, associated with the left hand cutter in Fig. 2, said member having a beaded lower edge 21 provided with a threaded recess 23, and a transverse aperture 24. This lock member is in the form of a plate extending longitudinally with the key, and it has a sliding fit in a recess 25 vertically aligned and communicating with the slot 14 in the cutter shank 6 and is retained in position by a rivet 26 extending through the walls of said recess and through the aperture 24, with the upper edge of the lock member positioned below the lower edge of the adjacent end of the key 12 (see Fig. 2.) When assembled in this relation, the surface of the upper edge of the lock member 20 extends longitudinally under the key, engages it, and prevents a tilting of the key 12 so that the key is positively locked against removal.

After first removing the rivet 26 the lock member 20 may be removed by the use of any suitable form of tool screwed into the threaded recess 23.

It will be apparent from the above that I have provided a structure in which the key when locked in assembled position, has no appreciable vertical movement within the key slots in the cutter shanks, or within the key slot in the spring rod, the lock member 20 serving as a means for positively insuring a coincident vertical movement of both cutters, the key, and the spring rod in both directions.

This is of great importance in that by such arrangement back-lash of the cutters relative to the key is prevented and the wear incident to such back-lash is eliminated.

Further with the ordinary key structure wherein the key slots in the cutters are of a height equal to the height of the center por-

tion of the key, the key is maintained in position only by the tension of the spring and the ends of the key being of lesser height than said slots permit an independent movement of one or both cutters upon the key. With such ordinary construction, if one of the cutters becomes jammed in the well bore an upward pull on the underreamer will cause the key to become twisted to an angled position with the corner of its medial projection wedging against the jammed cutter, then upon a downward movement such corner will be forced into the key slot of such jammed cutter with the result that all the parts become locked together against movement. If the parts cannot then be released by operation of the jaws of the tool string, the tool must be forcefully pulled from the well with the result that one or both of the cutters engaging the casing shoe will be broken and lost from the tool.

By preventing an independent movement of the cutters on the key the structure of the present invention eliminates any such wedging or jamming of the parts.

While the form of device herein illustrated and described is well adapted for the purposes primarily stated, it is to be understood that I do not wish to confine the invention to the one embodiment herein disclosed, for it is susceptible of embodiment in various other forms all coming within the scope of the claims which follow.

I claim:

1. In an underreamer, the combination of a body, a spring rod mounted in the body and provided with a transverse key-receiving slot, opposed cutters having shanks provided with key-slots substantially aligned with the key-slot of the rod, a cutter-supporting key insertable in an inclined position through the aligned slots when the spring rod is in a depressed position with its slot aligning with the slots of the opposed cutters, and a lock-member seated in the side of one of the cutters, having an upper edge with its surface extending longitudinally under, and engaging, the edge of said key for maintaining the key against displacement, said lock-member being removable to permit withdrawal of the key, the slot of the cutter opposite the locking member being of greater length than the depth of the end of the key engaging therein, to permit clearance in inserting the key.

2. In an underreamer, the combination of a body, a pair of oppositely disposed cutters with slots therein, a spring-rod disposed between the cutters and carried by the body, said spring rod having a slot therein, a key received in said slots, the slot in one of said cutters being of sufficient vertical width to receive the adjacent end of the key and substantially engage the upper and lower edges of the key, the slot in the other cutter being

- of considerably greater vertical width than the end of the key to permit tilting the key when inserting or withdrawing the same, the last-named of said cutters having a re-
 5 movable locking member for engaging the lower edge of the key to prevent the same from being moved downwardly at that end, the upper edge of the key at the end remote from said locking member being inclined to
 10 facilitate the downward movement of the end of the key adjacent the locking member when the key is being removed.
3. In an underreamer, the combination of a body, a pair of oppositely disposed cutters with slots therein, a spring-rod disposed between the cutters and carried by the body, said spring rod having a slot therein aligned with the slots in the cutters, a key having a wing at its middle portion and received in
 20 the slot of the spring-rod, the slot in one of said cutters being of sufficient vertical width to receive one end of the key and substantially engage the key on its upper and lower edges, the slot in the other cutter being of
 25 considerably greater vertical width than the adjacent end of the key to permit tilting the key when inserting or withdrawing the same, the last-named cutter having a recess adjacent the end of the key, extending from
 30 the outer face of the cutter inwardly toward the axis of the body, and a locking member removably mounted in said recess and engaging the adjacent end of the key to retain the same.
- 35 4. In an underreamer, the combination of a body, a spring-rod mounted therein and having a slot, a pair of oppositely disposed cutters carried by the body and having slots opposite the slot in the spring rod, a key having its ends received in the slots of the cutters and having a wing projecting up-
 40 wardly on the upper edge of the key and engaging the inner sides of the cutters to prevent displacement of the key, the slot in
 45 one of said cutters being of sufficient vertical width to receive the adjacent end of the key and substantially engage the key on its upper and lower edges, the slot in the other cutter being of considerably greater vertical width
 50 than the adjacent end of the key, so that the slot in that cutter extends downwardly below the key to permit the adjacent end of the key to be depressed in inserting or withdraw-
 55 ing the key, the last named cutter having a recess in the side thereof adjacent the end of the key, a locking member removably mounted in said recess and engaging the adjacent end of the key to retain the same, the upper edge of the key at the end thereof re-
 60 mote from the locking member having an inclined portion to facilitate the removal of the key when the locking member has been removed.
5. In an underreamer, the combination of a body, a spring rod mounted therein and having a slot, a pair of oppositely disposed cutters carried by the body and having slots opposite the slot in the spring rod, a key having its ends received in the slots of the cutters, passing through the slot of the
 65 spring rod and having a wing projecting upwardly and engaging the inner sides of the cutters to prevent displacement of the key, one of the slots of said cutters extending downwardly to permit the adjacent end of
 70 the key to be depressed to permit withdrawal of the key from the slots, a recess in the side of the cutter adjacent that end of the key, said recess extending from the outer face of the cutter inwardly toward the axis of the body and the locking member removably mounted in said recess and engaging the adjacent end of the key to retain the same, a transversely disposed pin passing through the locking member, and the body carrying
 75 the same, operating to prevent outward movement of the locking member.
6. In an underreamer, the combination of a body, a spring rod mounted therein and having a slot, a pair of oppositely disposed cutters carried by the body and having slots opposite the slot in the spring rod, a key having its ends received in the slots of the cutters, passing through the slot of the
 80 spring rod and having a wing projecting up-
 85 wardly and engaging the inner sides of the cutters to prevent displacement of the key, one of the slots of said cutters extending downwardly to permit the adjacent end of
 90 the key to be depressed to permit withdrawal of the key from the slots, a recess in the side of the cutter adjacent that end of the key, said recess extending from the outer face of the cutter inwardly toward the axis of the body and a locking member removably mounted in said recess and engaging the adjacent end of the key to retain the same, the lower edge of said locking member being
 95 enlarged to form a bead, said recess receiving said bead and cooperating therewith to prevent an upward movement of the locking member in the recess, and means for retaining the locking member in its recess.
